UNITED STATES PATENT OFFICE.

JOSEPH H. PENGILLY, OF LOS ANGELES, CALIFORNIA, ASSIGNOR TO BROWN & PENGILLY, INC., OF LOS ANGELES, CALIFORNIA, A CORPORATION OF CALIFORNIA.

QUICK-BREAK SWITCH.

Application filed June 29, 1925. Serial No. 40,230.

My invention relates to an improved form of electrical knife switch. When engagement is broken between the blades and break jaws of an ordinary knife switch, arcs are formed therebetween just as separation takes place. These arcs burn away the contacts. It is highly desirable to have a quick breaking of the blades and break jaws so that there will be but a minimum of arcing and a minimum of burning of the contacts.

It is an object of my invention to provide a switch in which engagement between the blades and break jaws will be quickly broken regardless of the rapidity with which the operating lever is moved. It is sometimes desirable to set a switch partly in the wall so that only the front part of the box extends therefrom. Switches intended for such setting are known as semi-flush switches.

It is a further object of my invention to provide a semi-flush switch having a novel quick break arrangement as mentioned above.

Other objects and advantages of my invention will be made evident hereinafter.

Referring to the drawings which are for illustrative purposes only,

Fig. 1 is a view of a switch embodying the features of my invention, the cover being broken away to show the internal construction.

Fig. 2 is a cross section taken on the line 2—2 of Fig. 1.

Fig. 3 is an enlarged fragmentary view showing in detail the quick break construction of my invention. The parts in this view are in the positions they occupy immediately previous to separation of the contacts.

Fig. 4 is a section taken on the line 4—4 of Fig. 3.

Fig. 5 is a view similar to Fig. 3, this view showing the contacts separated.

With reference to Figs. 1 and 2 a preferred embodiment of my invention comprises a box 11 having an interior 12 and a cover 13 for covering the front thereof, this cover being swingable so that access to the interior of the box may be had. An insulation base-board 15 is secured to a bottom 16 of the box 11 by bolts 17 which extend through the board 15 and through inwardly pressed portions 18 of the bottom 16. Break jaws 20 are secured near the upper end of the board 15 by bolts 21 which extend

from the board 15 through flanges 23 of the break jaws 20. Current carrying wires 24 are connected to the break jaws 20 by means of connectors 25. The wires 24 are connected to the connectors 25 and the connectors 25 are secured to the flanges 23 by the bolts 21, this being best shown in Figs. 1 and 2. Hinge jaws 27 are secured to the board 15 and blades 28 are pivoted to the hinge jaws 27 by pivot bolts 29. The hinge jaws 27 are connected to the upper fuse retainers 31 which carry upper ends of fuses 32. The lower ends of the fuses 32 are carried in lower fuse retainers 34. Connectors 35 are secured in contact with the lower fuse retainers 34 by bolts 36. Wires 37 are joined to the connectors 35.

A cross bar 39 is connected to the blades 28 by angles plates 41. Extending forwardly from the cross bar 39 are plungers 43 which are secured thereto by nuts 44 and 45 which are threadably secured on the plungers 43 at each side of the cross bar 39. Plunger portions 47 of the plungers 43 are bent downwardly a slight distance and extend through openings 48 formed in cross bars 49 of stirrups 51. Legs 53 of the stirrups 51 have openings 54 through which a crank portion 55 of an operating member 56 extends. The operating member 56 extends through side walls 58 of the box 11 and one end thereof is provided with an opening lever 60. The crank 55 is eccentric of bearing portions 61 of the operating member 56, which bearing portions extend through openings 62 in the side walls 58 and therefore the crank portion 55 is swung through an arc when the lever 60 is manipulated. Heads 64 are formed on the ends of the plungers 43 which extend through the openings 48 of the stirrups 51. Coil springs 65 are placed between washers 66 and 67 between the heads 64 and the cross bars 49 of the stirrups 51. As clearly shown in Fig. 4, engagement lugs 70 are bent inwardly from the legs 53 of the stirrups 51 and are adapted to be engaged by the washers 67.

When the switch is closed, the blades 28 are situated between the lips 72 of the break jaws 20. When the circuit which this switch controls is to be broken, the operating lever 60 is swung in a manner to move the blades 28 from the positions shown in Fig. 2 into the positions shown in Fig. 5. When the operating lever 60 is swung, the operating

member 56 pivots in the opening 62 on the bearing 61 and the crank 55 swings forwardly. A relative movement between the stirrups 51 and the plungers 43 occurs at this time, compressing the springs 65. Frictional engagement between the break jaws 20 and the blades 28 is sufficient to restrain the blades against movement at this time. When the operating member 56 has been moved to the extent shown in Fig. 3, the engagement lugs 70 engage the washers 67 placed on the plungers 43. This engagement gives positive contact between the operating member 56 and the blades 28. As the operating member 56 is swung farther, positive engagement supplied by the contact between the engagement lug 70 and the washers 67 moves the blades 28 forwardly therewith. As the blades move forwardly, less area is in engagement with the break jaws 20 and the frictional contact is therefore reduced. When the force of the frictional contact between the break jaws and the blades becomes less than the force of compression of the springs 65, the springs 65 will expand and very quickly remove the blades 28 from the position shown in Fig. 3 into the position shown in Fig. 5. When the switch is to be closed, the lever 60 is swung backwardly. The cross bars 49 of the stirrups 51 engage the nuts 45 and give positive engagement between the operating member 56 and the blades 28. As the lever 60 is swung, the blades 28 are readily swung into engagement with the break jaws 20.

The operating lever 60, as noted in Figs. 1 and 2, extends from one side of the box 11. However, it extends therefrom at a point near the front of the box. This allows the box to be set in a wall a considerable distance without interference to the operation of the lever.

From the foregoing description it is obvious that the break jaws and the blades will be separated very rapidly no matter how slow the operating member 56 is swung. There is no movement of the blades 28 until the engagement lugs 70 engage the washers 67. At this time there is a compression of the springs 65 and there is a resilient compressive force pulling forwardly on the plungers 43, this force however not being sufficient to overcome the frictional engage-

ment of the break jaws and the blades. As soon as the frictional engagement of the break jaws and the blades is reduced so that it is overcome by the compression of the spring 65, a relative movement takes place between the stirrups 51 and the plungers 43 which rapidly removes the blades 28 from engagement with the break jaws 20, as shown in Fig. 3, into non-engaging position as shown in Fig. 5. Such an arrangement as this absolutely prevents a slow separating of the break jaws and blades and thus reduces arcing therebetween to a minimum. With such an arrangement as shown in the drawings, the life of the switch is greatly prolonged.

I claim as my invention:

1. In a switch, the combination of: a base; jaws secured to said base; pivoted blades so placed as to close the circuits between said jaws; a cross bar secured to said blades; an operating member; a plunger rigidly secured to said cross bar and projecting outwardly therefrom; a stirrup hinged upon said operating means and having an opening through which said plunger projects; a compression coil spring surrounding said plunger and bearing at one end on said stirrup and at the other end on the outer end of said plunger; and means formed on said stirrup for limiting the compression of said spring.

2. In a switch, the combination of: a base; jaws secured to said base; pivoted blades so placed as to close the circuits between said jaws; a cross bar secured to said blades; an operating member; a plunger rigidly secured to said cross bar and projecting outwardly therefrom; a stirrup hinged upon said operating means and having an opening through which said plunger projects; a compression coil spring surrounding said plunger and bearing at one end on said stirrup and at the other end on the outer end of said plunger; and lugs formed on said stirrup and projecting into the path of a head formed on said plunger for limiting the compression of said spring.

In testimony whereof, I have hereunto set my hand at Los Angeles, California, this 24th day of June, 1925.

JOSEPH H. PENGILLY.
